Attorney

UNITED STATES PATENT OFFICE.

DONAT F. BOUCHER, OF NORTHBRIDGE, MASSACHUSETTS.

PAPER BAG.

Application filed March 7, 1922. Serial No. 541,783.

To all whom it may concern:

Be it known that I, DONAT F. BOUCHER, a citizen of the United States, residing at Northbridge, in the county of Worcester and State of Massachusetts, have invented 5 certain new and useful Improvements in Paper Bags, of which the following is a specification.

This invention relates to bags, having 10 more particular reference to paper bags such as are used in shops of various kinds as containers for articles sold.

The invention has for an object the provision of a novel type of bag of this sort 15 which is arranged to facilitate the packaging of such articles.

For further comprehension of the invention, and of the objects and advantages thereof, reference will be had to the following description and accompanying drawings, and to the appended claim in which the various novel features of the invention are 20 more particularly set forth.

Fig. 1 of the drawings is a perspective 25 view of my improved bag, showing it opened out but unfilled.

Fig. 2 is a fragmentary vertical sectional view of the bag as filled to maximum capacity and closed.

Fig. 3 is a fragmentary vertical sectional view of the bag as filled to less than maximum capacity, and with the closure elements arranged differently than in Fig. 2.

Referring now to the drawings the body 30 10 of the bag may be of usual construction and arranged in the usual manner for flat folding. According to my present invention I form integral with one wall of the

bag, at the mouth thereof, a tab 15 of considerable length and of substantially equal width to the bag. The length of the tab 15 is preferably approximately double the front to rear dimension of the expanded bag and it is provided on its inner face with a glue coating 16 which extends only over the outer half thereof. According as may be desired, depending on whether the article placed in the bag fills the latter to maximum capacity or less, the tab 15 may be either glued to the front of the bag as shown in 40 Fig. 2, or may be doubled upon itself and inserted into the top of the bag with the glued face turned upward, as shown in Fig. 3, the top edges of the bag being folded and glued to this face. The need of strings for 45 tying the bag is thus done away with.

Having thus described my invention what I claim as new and desire to protect by Letters Patent of the United States is as follows:

In a packaged article, a container of flexible material having an integral tab formed on one side of the mouth thereof and of equal width thereto, said tab being of approximately double the front to rear dimension of the container and being doubled upon itself within the mouth of the container the outwardly facing part of the tab having a coating of glue applied thereto, the lip on the opposite side of the mouth being 50 glued down upon this outwardly facing part of the tab.

In testimony whereof I have affixed my signature.

DONAT F. BOUCHER.
